[57] CLAIM

The ornamental design for an electric reflector lamp, as shown and described.

DESCRIPTION

FIG. 1 is a front perspective view of an electric reflector lamp, illustrating our new design;

FIG. 2 is a front elevational view thereof;

FIG. 3 is a rear elevational view thereof; and

FIG. 4 is a side elevational view thereof, the opposite side view, as well as the top and bottom views thereof, being substantially identical to FIG. 4.

The showing of a lamp capsule in FIGS. 1 and 2 is for the purpose of illustrating environmental use only.

FIG.1

FIG.2

FIG.4
